UNITED STATES PATENT OFFICE.

EDWIN H. BRODEN, OF EDGEWOOD PARK, AND JAMES G. MUSTIN, OF WILKINSBURG, PENNSYLVANIA, ASSIGNORS TO THE AMERICAN STEEL & WIRE COMPANY OF NEW JERSEY, OF HOBOKEN, NEW JERSEY, A CORPORATION OF NEW JERSEY.

COLLAPSIBLE REEL.

1,017,130.

Specification of Letters Patent. Patented Feb. 13, 1912.

Application filed September 22, 1911. Serial No. 650,786.

To all whom it may concern:

Be it known that we, EDWIN H. BRODEN, of Edgewood Park, and JAMES G. MUSTIN, of Wilkinsburg, both in the county of Allegheny and State of Pennsylvania, have invented certain new and useful Improvements in Collapsible Reels, of which the following is a specification.

Our invention relates to reels upon which wire, barbed wire fencing or similar material is reeled or coiled into bundles for convenience in storage and shipment.

Heretofore, the reels upon which such materials have been bundled frequently become broken or otherwise damaged by the rough usage to which the bundled materials are subjected during the frequent handlings necessary in storing and shipping, owing to a lack of strength in the wood forming the major portion of the reels.

The use of wooden reels is becoming more and more expensive owing to the increasing cost of wood and the cost is further increased owing to the practice of discarding or destroying the wooden reels after being once used when the wire or other material bundled thereon has been removed in being applied to its ultimate use.

One object of our invention is to provide a collapsible or "knock-down" reel formed entirely of metal and adapted for use repeatedly in coiling successive quantities of wire, barbed wire fencing and similar materials into bundles thereon in convenient shape for storage and shipment.

Another object of the invention is to provide a metal reel which combines extreme lightness in weight with very great strength, which is easily and cheaply made, and in which the parts forming the empty reel are detachably held together without the use of rivets, bolts and similar fastenings.

A further object of this invention is to provide a reel of novel construction by which when one lot of wire or other material bundled thereon has been removed is readily taken apart and shipped in disconnected or dismantled condition to the factory where the detached parts of the reel are again assembled together in readiness for continued use in receiving another quantity of wire or other material being bundled.

A still further object of our invention is to provide a reel capable of sustaining the

rough handling to which the filled reels are subjected in being stored and shipped from place to place, after each of the frequently repeated and practically unlimited number of successive wire bundling operations.

Referring to the accompanying drawings forming part of this specification, Figure 1 is a perspective view showing one form of a collapsible reel formed entirely of metal and constructed and arranged in accordance with our invention. Fig. 2 is a similar perspective view showing a modified form of all metal reel also constructed and arranged in accordance with this invention. Fig. 3 is a detail plan showing the construction of the endless wire ring forming the tie members of the reel. Fig. 4 is a detail side elevation of the ring shown in Fig. 3. Fig. 5 is a detail plan showing the construction of the endless wire rings employed in forming the end members of the reels shown in Figs. 1 and 2. Fig. 6 is a side elevation of the wire ring shown in Fig. 5. Fig. 7 is a perspective view showing a further modification in the construction of reels formed in accordance with our invention. Fig. 8 is a detail plan and Fig. 9 a longitudinal side elevation of the end members employed in forming reels as shown in Fig. 7.

In the drawings 2 designates the endless wire rings forming the cross pieces or tie members and 3 the wire rings forming the end members of the reel which are detachably secured together in their spaced apart position by the tie members 2 when the parts are assembled together in place to form the reels. The ends of the wire forming the rings 2 and 3 preferably are welded together as shown in the drawings although the ends may be twisted together in forming the rings when found necessary or desirable. As is shown in detail Figs. 3 and 4, the rings 2 forming the tie members are bent so as to be rectangular in plan and, adjacent to each corner, the wire is reversely bent to form indentations or notches 4 and 5 which extend in planes at right angles to each other. The rings or hoops 3 forming the end members of the reel have semi-circular ends connected by side portions which are slightly bowed outwardly or which may have substantially parallel sides, the outwardly bowed construction shown in Fig. 5 preferably being used. The rings 3 have inwardly

bent curved indentations or notches 6 located at two separated points in the length of the oval ring on each of the bowed side portions thereof.

- 5 In assembling the end members and tie members to form the reels of Fig. 2 the rings 2 are slipped over the ends of the rings 3 and are moved inwardly thereon until the notches 4 on the rings 2 engage with the notches 5 in the rings 3, the curved side portions of the rings 3 being sprung inwardly sufficiently for this purpose. The side portions of the rings 3 then spring outwardly with enough force to yieldingly hold 10 the notched portions in engagement with each other and the notches preventing relative movement and maintaining the parts together in place in assembled position and permit handling of the empty reels.
- 15 In the construction shown in Fig. 1 two of the rings 3 are employed in forming each end member of the reel and the two rings 3 are placed together so as to extend lengthwise at right angles to each other with the curved portions of the wires forming the indentations 6 on each ring 3 in engagement with each other. The rings 2 are then slipped over the opposite ends of one of the two rings 3 forming each end member of the reel 20 until the indentations 4 thereon are in engagement with the indentations 6 in one ring 3 and the indentations 5 in engagement with the indentations 6 on the other of each pair of rings 3 forming in the construction 25 of Fig. 1 the end members of the reel.
- 30 In the construction shown by Figs. 7, 8 and 9 each of the two end members of the reel is formed of two metal plates 7 instead of a wire ring as in the preceding figures.
- 35 The two plates forming each end member extend lengthwise at right angles to each other and their marginal edges have notches or indentations 8 which correspond to the indentations 6 in the rings 3. The rings 9 forming in this construction the tie members 40 of the reel are similar to the rings 2 of Figs. 1 to 6 and the indentations 4 and 5 thereon engage with the end members 8 and with each other in a similar manner in securing 45 the parts of the reel together in assembled relation. Openings 10 in the center of each plate 7 are provided, through which the spindle of a reeling machine extends when coiling or reeling wire upon the reel of Fig. 50 7, and the openings or holes 11 provided on the opposite ends of each plate 7 afford means for securing the outer ends of the end members of the reel together when filled with wire, a wire threaded through these 55 holes having its ends fastened together to tie the ends of the plates forming the end members of the reel together. While two of the plates 7 are employed in forming each end member of the reel of Fig. 7 obviously 60 one may be employed to form the end mem-

ber in a similar manner to that shown in Fig. 2 when desired. The reels, for the sake of clearness, are shown in Figs. 1, 2 and 7 without any wire or other material bundled thereon.

70 The assembled reels are used as required, being placed in position upon a reeling machine and wire then being reeled or wound thereon between the end members until a bundle is formed of a diameter corresponding approximately to the length or greatest dimension of the end members. The so-formed bundles are then in readiness for storing or shipment to the place of use. After the wire has been removed for use, the 80 empty reels are easily and quickly taken apart by hand and, when a quantity of the dismantled reels have been accumulated, they are returned in collapsed or disconnected condition to the factory where they are 85 again readily assembled together in readiness for further use.

85 The advantages of our invention will be apparent to those skilled in the art.

90 By taking the reels apart for shipment damage to the empty reels is avoided while the space occupied during shipment is very greatly lessened.

95 Modifications in the construction and arrangement of the parts may be made without departing from our invention as defined in the claims.

We claim:

1. A collapsible reel comprising metal cross arms forming end members, and wire 100 rings forming tie members to connect the end members in spaced apart relation, the overlapping contacting marginal surfaces of at least part of the tie members and end members being indented, to thereby yieldingly secure and detachably hold said several members forming the empty reel together in assembled relation.

105 2. A collapsible reel comprising cross arms forming end members, and wire rings forming tie members to connect the end members in spaced apart relation, the overlapping contacting marginal surfaces of the tie members and end members being indented, to thereby yieldingly secure and detachably hold said several members forming the empty reel together in assembled relation.

110 3. A collapsible reel comprising wire rings forming end members and forming tie members to secure the end members in spaced apart relation, said rings being indented adjacent to the intersecting points thereon contacting with one another when assembled together to thereby yieldingly and detachably secure the members forming the empty reel 115 in their spaced apart relation.

120 4. A collapsible reel comprising elongated wire rings forming end members and forming tie members to secure the end members in spaced apart relation, each end member 125

being formed of two of said rings and arranged with their long axes at right angles to each other, said rings being indented adjacent to the intersecting points thereon contacting with one another when assembled together to thereby yieldingly hold and detachably secure the members forming the empty reel in spaced apart relation.

5. A collapsible reel comprising a plurality of endless wire rings forming spaced apart end members and tie members, said several members having indentations engaging with the intersecting member contacting therewith whereby the end and tie members forming the empty reel are detachably held together in assembled position.

10. A collapsible reel comprising ring members formed of wire and connecting the spaced apart cross-arms forming opposite end members, the marginal edges of the ring members and the cross-arms being indented adjacent to the contacting edge portions of the intersecting members to thereby detachably secure and yieldingly maintain the several members forming the empty reel together in assembled position.

15. A collapsible reel comprising ring mem-

bers formed of wire and connecting spaced apart cross-arms forming the opposite end members, the arms forming each end member being rectangular in outline and extending lengthwise at right angles to each other, the marginal edges of the ring members and cross-arms forming the head members being indented adjacent to the contacting edge portions of the intersecting members to thereby detachably secure and maintain the several members forming the empty reel together in assembled position.

20. A collapsible reel comprising ring members formed of wire connecting spaced apart metal end members, the marginal edges of the end members and ring members being indented adjacent to the points of contact of their intersecting members to thereby detachably secure and maintain the members of the empty reel in assembled position.

25. In testimony whereof, we have hereunto set our hands.

EDWIN H. BRODEN.
JAS. G. MUSTIN.
